GOLF PUTTER HEAD

Raymon W. Cook, San Antonio, Tex., assignor to Ray
Cook Golf Putters, Inc., San Antonio, Tex.

Continuation of design applications Ser. No. 293,527,
Sept. 29, 1972, and Ser. No. 343,386, Mar. 21, 1973,
both now abandoned. This application June 14, 1974,
Ser. No. 479,460

Term of patent 14 years

Int. Cl. D21—02
U.S. Cl. D34—5 GH

FIG. 1 is a front elevational view of a golf putter head showing my new design.

FIG. 2 is a front end view of FIG. 1.

FIG. 3 is a top plan view of FIG. 1.

FIG. 4 is a rear elevational view of FIG. 1.

FIG. 5 is a vertical sectional view, taken on the line 5-5 of FIG. 4, looking in the direction of the arrows.

FIG. 6 is a bottom plan view of FIG. 1.

FIG. 7 is a front elevational view of another embodiment of my design.

FIG. 8 is a front end view of FIG. 7.

FIG. 9 is a top plan view of FIG. 7.

FIG. 10 is a rear elevational view of FIG. 7.

FIG. 11 is a vertical sectional view, taken on the line 11-11 of FIG. 10, looking in the direction of the arrows.

FIG. 12 is a bottom plan view of FIG. 7.

This application is a continuation of design patent application D. 293,527 filed Sept. 29, 1972 and design patent application D. 343,386 filed Mar. 21, 1973, both now abandoned.

I claim:
The ornamental design for a golf putter head, as shown and described.
